Primary Examiner — Keith J Wilson(74) *Attorney, Agent, or Firm* — Volpe Koenig(57) **CLAIM**

The ornamental design for a faucet stream straightener as shown and described.

DESCRIPTION

FIG. 1 is a top plan view of a faucet stream straightener in accordance with my design;

FIG. 2 is a top, front perspective view thereof;

FIG. 3 is a bottom plan view thereof;

FIG. 4 is a bottom, front perspective view thereof;

FIG. 5 is a rear elevational view thereof;

FIG. 6 is a right side elevational view thereof;

FIG. 7 is a front elevational view thereof; and,

FIG. 8 is a left side elevational view thereof.

1 Claim, 8 Drawing Sheets(56)
